UNITED STATES PATENT OFFICE

156,057

DESIGN FOR A PAPER KNIFE

Cornelius Vander Kuy, Holland, Mich.

Application October 21, 1948, Serial No. 149,215

Term of patent 3½ years

(Cl. D74—1)

To all whom it may concern:

Be it known that I, Cornelius Vander Kuy, a citizen of the United States, residing at Holland, in the county of Ottawa and State of Michigan, have invented a new, original, and ornamental Design for a Paper Knife, of which the following is a specification, reference being had to the accompanying drawing, forming a part thereof, in which:

Fig. 1 is a side elevational view of a paper knife, showing my new design, the opposite side presenting substantially the same appearance as the side shown;

Fig. 2 is an edge elevational view thereof;

Figure 3 is a sectional view on line 3—3 of Figure 1;

Figure 4 is a sectional view on line 4—4 of Figure 1; and

Figure 5 is a sectional view on line 5—5 of Figure 1.

I claim:

The ornamental design for a paper knife, as shown.

CORNELIUS VANDER KUY.
